UNITED STATES PATENT OFFICE.

WILLIAM W. LOCKWOOD AND CHANCLA M. BICKFORD, OF FREEPORT,
KANSAS.

GRAIN-METER.

SPECIFICATION forming part of Letters Patent No. 405,315, dated June 18, 1889.

Application filed March 6, 1889. Serial No. 302,127. (No model.)

To all whom it may concern:

Be it known that we, WILLIAM W. LOCKWOOD and CHANCLA M. BICKFORD, citizens of the United States, residing at Freeport, in the county of Harper and State of Kansas, have invented certain new and useful Improvements in Grain-Meters; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in automatic grain-weighers; and it has for its object to simplify, cheapen, and render more efficient in operation this class of devices.

The invention consists in the peculiar combinations and in the construction, arrangement, and adaptation of parts, all as more fully hereinafter described, shown in the drawings, and then specifically defined in the appended claims.

The invention is clearly illustrated in the accompanying drawings, which, with the letters of reference marked thereon, form a part of this specification, and in which—

Figure 1 is a perspective view showing our invention. Fig. 2 is a vertical section through the same. Fig. 3 is a rear view. Fig. 4 is a side elevation of a slightly modified form with parts broken away.

Like letters refer to like parts throughout the several views.

Reference now being had to the details of the drawings by letter, A designates a suitable tube adapted to be connected at its upper end with an elevator-tube or other outlet, (not shown,) from which the material to be weighed finds its way into the said tube A. At its lower end this tube A is broadened out 45 or enlarged, as shown, and divided by means of the vertical partition a into two compartments A' and A².

Journaled in suitable bearings transversely of this tube is the shaft B, one end of which 50 extends through the side wall of the tube, and

is bent at right angles, as shown, to form the arm or lever b. This shaft B is arranged a short distance above the top of the partition a, and has secured thereto, so as to move with it, the door or switch-board B', arranged to alternately open and close the entrance to the compartments A' and A² and the outlet to the tube A by the mechanism and in the manner hereinafter described.

b' are washers on the shaft B, one upon each side of the switch-board B', and are for the purpose of preventing contact of said switch-board with the side walls of the tube, whereby said switch-board moves with little friction. This switch-board is formed or provided with a tail-piece B², which extends below the shaft on which the switch-board is pivoted; and extends in the same general line with said switch-board, so, as the said board is turned, the tail-piece serves to guide the material away from the partition a and prevents the same from accumulating on the top of the said partition.

Secured to the opposite sides of the tube A, at the discharge end thereof, in line with the partition a, are the ears C, slotted vertically, as shown at c, and working in the slots of said ears is the transverse shaft D, having elongated heads d outside said ears, and between said ears is hinged or pivoted in any suitable manner the trap-door E, one-half of which is arranged at an angle of about one hundred and thirty-five degrees to the other half, as shown, and arranged to alternately open and close the outlet to the compartments A' and A² in a manner and through the medium of the devices which will be hereinafter described.

Projecting from the side of one-half of the trap-door E is the pin e, which engages the elongated loop or eye f on the lower end of the rod F, the upper end of which is pivotally connected with the arm on the lever b on the transverse shaft B in any suitable manner, preferably, however, as shown in the drawings—that is, by means of a hook f', engaging a hole f² in the free end of said arm b.

Suitably journaled in bearings on the tube A, at a height of about that of the top of the partition a, is the transverse shaft G, one end 100

of which extends through the wall of the tube, and is bent at right angles, so as to form the arm or lever *g*, the free end of which is provided with a hole *g'*, with which engages the hooked end *h* of the rod *H*, the lower end of which is formed with a vertically-elongated loop or eye *h'*, which loosely engages the shaft *D* between the ear *C* and the elongated head *d*. Secured to the other end of the shaft *G* is the scale-beam *I*, the short arm of which is provided at its free end with a hole *i*, into which is engaged the hooked end *j* of the rod *J*, the lower end of which rod is formed with a vertically-elongated loop or eye *j'*, which loosely engages the shaft *D* between the ear *C* and the elongated head *d*. The long arm of the scale-beam *I* is graduated or marked off into pounds, as shown at *i'*, and sleeved on this long arm is the adjustable weight *I'*, provided with the set-screw *I''*, by means of which said weight may be held in its adjusted position on the beam. On the short arm of the beam is an adjustable weight *I''* for the purpose of balancing the scales, and provided with a set-screw *i''* to hold said weight in its adjusted position. One end of the shaft *D* is extended and bent upward at right angles, as shown, to form the arm or dog *D'*, the free end of which is broadened and flattened, as shown at *d'*.

K K are blocks on the side of the tube *A*, and pivoted upon each one of these blocks is a latch or dog *L*, provided with a shoulder or notch *l*, and *M M* are springs secured to said blocks and bearing on the top of said dogs or latches, as shown.

m m are stops on said blocks to limit the downward movement of said latches or dogs.

Upon one side of the tube *A* is a registering device, consisting of the three ratchet-wheels *N O P*, each having teeth numbered from 1 to 0, and the two wheels *N* and *O* each provided with a deep notch *n* and *o*, respectively, as is common in this class of devices, and so arranged that the wheel *N* will be rotated alone until it has moved ten times, when the dog hereinafter described will fall into the deep notch, allowing said dog to engage the wheel *O*, and so on, in a manner well understood.

Pivoted on the shaft *n'* of the ratchet-wheels is the bell-crank lever *Q*, to the upper end of which is pivoted one end of the dog *R*, the other end of which is formed with the two notches *r* and *r'*, of different depth, and arranged to engage the teeth of the ratchet-wheels in the manner above described, and which will be readily understood. The other arm of this bell-crank lever *Q* is pivotally connected by means of the rod *S* with one of the halves of the drop-door *E*, said rod passing through a guide-opening *k* in one of the blocks *K* on the side of the tube *A*.

The tube *A* and the compartments *A'* and *A''* may be of any desired capacity, according to the amount of grain or other material that it is proposed to weigh at a time, the marks

upon the scale-beam and wheels of the registering device being made to correspond with the capacity of said compartments—that is, if the compartments are each of two thousand pounds' capacity, then the marks upon the scale-beam would indicate tons, and the figures upon the wheels tons, and so on. In case the last or any amount emptied into one of the compartments should be less than the capacity thereof and for which the device is set, it can be readily weighed by loosening the set-screw of the weight on the long arm of the scale-beam and moving said weight carefully back on the beam until the measure is dumped, and noting the weight upon the beam.

Although we have not so shown it, the device or the machinery or mechanism pertaining to the weighing of the grain or other material should be suitably inclosed and a door provided to the register, and said door having a glass-covered opening opposite the *O*'s upon the ratchet-wheel, as is common in this class of devices, but to which no claim is made in this application. When made upon a smaller scale and adapted for use by millers or farmers for measuring grain, the lower end of the tube *A* is reduced to the same size, or nearly the same size, of the portion of the tube above the partition in the enlarged portion, as shown at *T* in Fig. 6, room being provided for the swinging of the trap-doors and for the exit of the grain, as shown in said figure.

U U are hooks attached to the sides of the portion *T*, as shown in said Fig. 6, and are designed to serve as sack-hooks over which to secure the mouth of a bag while the same is being filled.

The operation of the device is simple and apparent. Having set the weight on the long arm of the scale-beam in the proper place to weigh the desired amount, engage the dog *D'* with the notch of one of the latches *L*. This closes one-half of the trap-door against the bottom of one of the compartments and throws the switch-board in position to close the entrance or mouth of the other compartment; as the compartment is filled. When the required amount of material has fallen on the trap-door, the said trap-door will be pressed downward, (the elongated slots in the ears and the elongated eyes or loops on the connecting-rods allowing of a slight movement bodily of the doors and the shaft on which they are pivoted,) and the dog *D'*, withdrawn from its engagement with the latch *L*, and the weight of the grain on the door throws said door open, and consequently closes the outer door against the bottom of the other compartment. The same movement reverses the switch-board, throws the scales on a balance, and latches the dog *D'* with the other latch *L*, and the device is ready to receive another charge, when the operation is repeated. Each time the trap-door is opened and closed the dog *R* is oper-

ated, through the mechanism above described, to actuate the ratchet-wheels of the registering device, and thus automatically register the amount of grain discharged.

5 The free end of the dog D² is provided with an anti-friction roller d⁵, to lessen the friction between the same and the latches, as will be readily understood.

What we claim as new is—

10 1. The combination, with the tube and the partition dividing the same into two compartments, of the hinged trap-doors pivoted at the discharge end of said compartments and having a limited vertical movement on 15 their pivots, substantially as shown and described, and for the purpose specified.

2. The combination, with the tube divided into compartments, as described, of the ears secured at the lower ends of said compartments and having elongated slots, the transverse shaft journaled in said ears and working in said slots, and the trap-doors carried by said shaft, substantially as shown and described.

25 3. The combination, with the tube and the partition a, of the pivoted switch-board, the trap-doors having vertical play and one of which is connected with said switch-board, and the scale-beam connected with the shaft 30 of said trap-doors, substantially as and for the purpose specified.

4. The combination, with the tube divided into compartments, as described, and the pivoted switch-board and hinged trap-doors having free vertical play, of the scale-beam, the shaft on which said beam is pivoted, the rod connecting an end of said shaft with the shaft of trap-doors, the rod connecting the short arm of the scale-beam with the other end of 40 said shaft, and the rod connecting switch-board with one of said trap-doors, substantially as and for the purpose specified.

5. The combination, with the tube, the vertical partition dividing the same into two compartments, and the pivoted switch-board above the partition, of the pivoted trap-doors beneath said receptacle, the pivoted scale-beam, the shaft to which beam is pivoted be-

ing extended across the tube and bent at right angles to form an arm, the rod connecting the 50 free end of said arm with the shaft of the trap-doors, and the rod loosely connecting the shaft of the switch-board with one of said doors, substantially as described.

6. The combination, with the pivoted switch-board, the pivoted scale-beam, and the shaft carrying the trap-doors, of the rod connecting the short arm of the scale-beam with one end of said shaft, and the rod connecting the free end of the shaft on which the scale-beam is 60 pivoted with the other end of the shaft carrying the trap-doors, substantially as described.

7. The combination, with the tube and the slotted ears secured thereto, of the transverse 65 shaft working in the slots of said ears, the enlarged heads on the ends of said shaft, the pivoted switch-board, the pivoted scale-beam, and the rods connected at one end with the short arm of the scale-beam and with the 70 shaft of the switch-board and the other end loosely engaging the shaft of the trap-doors between the ears and the enlarged heads, substantially as shown and described.

8. The combination, with the tube and the 75 pivoted latches thereon, of the pivoted trap-doors, and the vertical extension of the shaft of said trap-doors provided at its free end with an anti-friction roller, substantially as shown and described.

9. The combination, with the tube and the pivoted trap-doors, of the blocks on said tube, the registering device, and the rod connected at one end to one of said doors passed through an opening in one of said blocks and 85 at the other end connected with the registering mechanism, substantially as shown and described.

In testimony whereof we affix our signatures in presence of two witnesses.
